UNITED STATES PATENT OFFICE.

PAUL KUEHN, OF DENVER, COLORADO.

AMALGAMATING DEVICE.

1,262,812.

Specification of Letters Patent. Patented Apr. 16, 1918.

Application filed August 12, 1916. Serial No. 114,510.

To all whom it may concern:

Be it known that I, PAUL KUEHN, a citizen of the United States of America, residing at Denver, in the county of Denver and State of Colorado, have invented certain new and useful Improvements in Amalgamating Devices, of which the following is a specification, reference being had therein to the accompanying drawings.

10 This invention relates to devices for recovering metals from their ores by amalgamation and more particularly to an improvement in the construction of amalgamators of the type shown in my Letters Patent No. 15,019,054, dated March 5, 1912, wherein amalgamation is effected by maintaining two hydrostatic columns of ore pulp upon a body of mercury and causing the pulp to flow from the bottom of one column to the 20 bottom of the other, by giving one column a slight head over the other, the pulp being caused to flow in a thin stream over the surface of an amalgam plate supported by the mercury, in passing from one column 25 to the other, the plate serving to prevent agitation and consequent flouting of the mercury and the body of the mercury beneath the plate serving to receive and hold the amalgam carried over the edges of the 30 plate by the flow. An object of this invention is to keep the surface of the amalgam plate over which the pulp flows in prime condition for effecting amalgamation, by continuously supplying fresh mercury to 35 said surface, and to accomplish the same in a very simple manner without hindering the flow of the pulp over the plate and without liability of flouting the mercury. It is also an object of the invention to provide a construction which will facilitate the "clean up" 40 or removal of the amalgam and make the parts interchangeable.

To these ends the invention consists in the matters hereinafter set forth and more particularly pointed out in the appended claims reference being had to the accompanying drawing in which—

Figure 1 is a transverse vertical section through a device embodying the invention; 50 and

Fig. 2 is a horizontal section of the same substantially upon the line X—X of Fig. 1.

It is preferable where a number of these devices are used, to make them so that the 55 several parts will be interchangeable, thus facilitating the "clean-up" or removal of

the amalgam by being able to take certain parts from one machine and place them in another while the removed parts are being put in condition for use. For this reason 60 the device as shown in the accompanying drawing is made up of an outer shell 1 of cylindrical form into which is set a separate cup or receptacle 2, said receptacle being properly centered within the shell in 65 any suitable manner as by forming a slight depression in the bottom of the shell. The hopper 3 is arranged to set upon the upper edge of the shell 1 and is held in place by an annular flange 4 engaging the shell. 70 This hopper is formed with a tubular downwardly extending feed tube 5 located and held in the center of the receptacle 2 by means of the hopper and the lower end of this feed tube is spaced from the bottom 75 of the receptacle by being suspended therein. When ore pulp is fed into the hopper a central hydrostatic column is formed in the feed tube 5 and the pulp flows from the bottom of this column laterally in the receptacle 2 and rises therein, overflowing the 80 upper edge of said receptacle.

To cause the ore pulp to flow for a certain distance laterally in the receptacle 2 before it rises therein, a false wall 6 of tubular form is secured to the bottom of the hopper in spaced parallel relation to the feed tube 5 and is connected to the lower end of the feed tube by a horizontal wall 7, thus forming between the wall 6 and the 85 wall of the receptacle 2, an annular hydrostatic column of ore pulp in said space 90 between said walls.

When the device is placed in operation a suitable amount of mercury indicated at 9 95 is placed in the bottom of the receptacle 2 and an amalgam plate 10 is placed in the receptacle to float upon this body of mercury with the narrow space between its upper surface and the lower end of the feed 100 tube 5 and horizontal wall 7. This plate 10 supports the center column of ore pulp and takes the impact of the down flow of said column, thus protecting the body of mercury and preventing the same from being 105 floured by the flow and carried upwardly with the flow and over the upper edge of the receptacle 2. In flowing laterally from the center column through the narrow space between the upper surface of the plate and the horizontal wall 7, the ore pulp is brought 110 into intimate relation with the mercury coat-

ed upper surface of the plate and thus every particle of precious metal is brought into contact with the mercury and amalgamated therewith.

5 It has been found that in an amalgamator of the type shown in my Letters Patent No. 1,019,054, the impact of the flow of pulp from the center column upon the amalgam plate soon wears away the mercury coating 10 of the plate, scouring it so that it is left clean at the center portion and thus permitting some of the pulp to flow over the plate without coming in contact with the mercury. To overcome this defect a hole 11 of the proper size is bored through the plate at the axis of the feed column, thus permitting the mercury to pass up through this center opening and flow radially over the surface of the plate, the weight of the center column of pulp causing the plate to be depressed slightly so that the tendency of the mercury will be to flow through this center opening, and the lateral flow over the plate from the center column radially 20 toward its outer edge, also tends to draw the mercury through the center opening and spread it over the upper surface of the plate which is thus automatically kept in prime condition at all times.

25 The amalgam plate 10 is preferably made with six or more straight sides and of such a diameter that the angles formed by these sides will just touch the circular wall of the receptacle 2 and thus hold the plate centered 30 within the receptacle with its center opening 11 at the axis of the receptacle and the center feed column. This leaves spaces between the straight edges of the plate and the wall of the receptacle, and through these spaces 35 the amalgam formed on the upper surface of the plate drops into the bottom of the receptacle and body of mercury beneath the plate. The radial movement of the pulp tends to force the amalgam formed on the upper surface of the plate outwardly and over its outer edge.

40

45

The hopper 3 is preferably made shallow so that the center column can only have a certain amount of head over the outer annular column in the receptacle and thus the 50 rate of flow of the pulp downwardly in the center column, radially in all directions from the lower end of the center column to the lower end of the annular column and upwardly and over the upper edge of the receptacle 2 is governed. The waste or overflow from the receptacle is discharged through a suitable spout on the outer shell.

55 By making the shell 1 the receptacle 2 and the hopper 3 with its center feed tube, in 60 separate parts which fit together, the "clean up" or removal of the amalgam from the receptacle is facilitated as the receptacle may be taken out with the amalgam and the 65 remainder of the pulp therein and set one

side, and another receptacle put in its place having the proper amount of mercury in its bottom and an amalgam plate floating on the mercury.

By providing the amalgam plate with the center opening in the arrangement of parts as shown, causes mercury to be constantly supplied to the surface of the plate and the mercury surface thus constantly renewed as it is scoured away by the contact of the pulp flowing thereover. This very essential feature of keeping the amalgam plate in prime condition during the operation of the device is thus secured in a very simple manner and the operation of the machine made continuous until such time as the space beneath the amalgam plate has been completely filled with amalgam. The size of this center opening 11 in the amalgam plate is made in proportion to the diameter of the plate and the size of the machine, and it is obvious that one or more openings may be provided in the plate opposite the lower end of the center feed column as found desirable.

Having thus fully described my invention 90 what I claim is:—

1. In an amalgamator, the combination of a receptacle, a body of mercury in said receptacle, an amalgam plate supported solely by the body of mercury, and means for 95 maintaining hydrostatic columns of ore pulp of different heights upon said plate and body of mercury, said plate having an opening therethrough at the lower end of one column within which the mercury rises and through 100 which the mercury from beneath the plate is adapted to pass.

2. In an amalgamator, the combination of a receptacle, of a body of mercury in the bottom of the receptacle, an amalgam plate 105 floating upon the body of the mercury, and having an opening therethrough, and a feed member extending downward into the receptacle to feed material by gravity with its lower end adjacent the upper face of the 110 amalgam plate and opposite the opening therein.

3. In an amalgamator, the combination of a receptacle, a body of mercury in the body of the receptacle, an amalgam plate floated 115 by the body of mercury, a feed tube extending down into the receptacle to feed material therein over the surface of said plate, said feed tube forming a hydrostatic column resting upon said plate and causing the plate 120 to be depressed slightly into the body of mercury, said plate having an opening therethrough within which the mercury rises when the plate is depressed.

4. In an amalgamator, the combination of 125 a receptacle, a body of mercury in the bottom of the receptacle, an amalgam plate floating upon said body of mercury, a feed tube extending downward into the receptacle for feeding material on to the plate, 130

and means whereby mercury is supplied to the upper surface of said plate at the lower end of said feed tube.

5. In an amalgamator, the combination of a circular receptacle, a body of mercury in the bottom of said receptacle, an amalgam plate floating upon the body of mercury and a tubular feed member extending downward within the receptacle with its lower end spaced a short distance from the upper surface of said plate and forming a center and

concentric hydrostatic columns of ore pulp of different heights, said amalgam plate being provided with an opening therethrough at the axis of the center column. 15

In testimony whereof I affix my signature in the presence of two witnesses.

PAUL KUEHN.
